FOLDING MECHANISM

Henry T. Scott, Toledo, Ohio, assignor to The American Paper Bottle Company, Toledo, Ohio, a corporation of Ohio

Application October 16, 1934, Serial No. 748,566

17 Claims. (Cl. 93—6)

The present invention relates to folding mechanism and particularly to mechanisms for folding and closing the foldable end portions of tubular containers. The present application is a continuation in part of my earlier application, Serial No. 603,861, filed April 7, 1932.

In my application, Serial No. 686,300, filed August 22, 1933, is disclosed and claimed a container fabricated of paper, and coated both exteriorly and interiorly with a liquid proofing substance such as paraffin, the container being primarily intended for the packaging, storage and dispensing of liquids. It is fabricated of relatively stiff paper, is square in cross section and 15 has an extension which is as disclosed, divided into panels by means of score lines and which extension is adapted to be collapsed or folded after the container has been charged to close the end thereof. In the complete operation of 20 closing the foldable end portion of the container, it is desirable that the integrity of the panels be maintained and that these panels be relatively folded only along the score lines specifically provided for that purpose when the blank was originally cut. In my copending application, Serial 25 No. 748,561, filed October 16, 1934, is described a mechanism for performing a preliminary operation upon the foldable end of the container, this mechanism effecting by its operation a partial 30 fold along the score lines, or a redefinition of the score lines, an operation particularly desirable where the container as a whole has been impregnated with paraffin and thereby considerably stiffened. In this redefinition of the score lines 35 of the end closure all or a portion only of the score lines may be redefined but in any event a sufficient redefinition of the score lines is realized to render the container end more readily collapsible by the means which comprises the subject matter of the present application.

The container disclosed in the application previously referred to includes, in its foldable end portion, not only a plurality of panels hingedly connected together along the score lines but also 45 two end flaps and it is desired that, in the closing operation, one of these end flaps be inserted into the mouth of the container and the other turned over so as to overlie the first mentioned flap and also the several plies of paper which are gathered 50 together in the closing operation to form what may be designated a central transverse rib. The present invention embodies a plurality of folding instrumentalities which are primarily designed and constructed for the manipulation of the end 55 closure panels and end flaps of a container such

as has been disclosed in my copending application and by means of which this operation may be rapidly and accurately carried out in an automatic manner. Nevertheless, the principles of the invention may be embodied in machines which 5 vary widely in the design and arrangement of their component elements and which are well adapted to effect the closure of the foldable or collapsible ends of tubes or containers of various designs and sizes. One embodiment of the invention is illustrated by way of example in the accompanying drawings, in which

Figure 1 is an end elevation of the closure folding mechanism;

Figure 2 is a side elevation of the same; 15

Figure 3 is a section on line 3—3 of Fig. 1;

Figure 4 is a section on line 4—4 of Fig. 2;

Figure 5 is a section on line 5—5 of Fig. 1;

Figures 6 to 11 inclusive are views, rather diagrammatic in section, which portray the several 20 movements of the folding members of the apparatus which these members perform in sequence in effecting the complete closure of a container;

Figure 12 is a perspective view of the foldable 25 end of a tubular container of the type disclosed in my copending application above referred to and which the mechanism now to be described is primarily intended to act upon;

Figure 13 is a perspective view of the upper end 30 of a container which is ready for closing; and

Figure 14 is a perspective view of the upper end of a closed container.

The container, partially illustrated in Figure 12, is formed of relatively stiff paper and is square in horizontal section, its bottom being closed and 35 the entire container being coated with paraffin exteriorly and interiorly. Its foldable end closure is indicated generally at C in Figure 12 and is seen to comprise a plurality of panel sections P which meet along score lines S. When in this 40 condition the end closure is relatively stiff and, prior to charging, it is desired that the score lines be redefined, either wholly or in part, by subjecting the panels to pressures which tend to move them into different planes while at the 45 same time maintaining the integrity of the panels by confining the flexure entirely to the score lines or hinge lines. A mechanism for redefining the score lines is described in my copending application, Serial 748,561, filed October 16, 1934, and 50 after the score lines are thus redefined the container end closure may have the appearance indicated in Figure 13. The container may then be charged with a liquid or with a solid after which 55 it is necessary to effect the final complete closure

of the container by collapsing inwardly two opposing side sections of the foldable extension and folding downwardly upon these previously collapsed side sections the remaining two side sections, the upper edges of all four side sections being gathered together to form a central transverse rib and the two end flaps being folded down to lie parallel with the plies of paper which comprise this rib. It is the function of the present apparatus to receive containers having end closures of the general type illustrated in Figure 12, and which closures have been subjected to a preliminary score redefining operation so that they are reduced to the condition shown in Figure 13, and to then act upon such closures to produce the closed, sealed container illustrated in Figure 14 which, when completed, is rigid, durable and leak proof.

In Figure 6 of the drawings means for performing the first operation of folding is illustrated. It will be perceived that the container is supported in such manner that its foldable upper end extension lies between opposing folding members. It is so positioned that the collapsible sides of the container are disposed in planes substantially parallel to the planes of movement of the folding members and its foldable sides are positioned so as to be directly acted upon by these folding members, the end flaps 10 and 11 being upward continuations of the foldable sides. The base of the container may be supported in any suitable manner but preferably rests upon supporting rails 12 and is preferably securely held between gripping members 13 forming parts of a conveyor chain 14 by means of which it may be moved with a step by step movement. For a more full and complete description of the container supporting and advancing means, reference may be had to my copending application, Serial 748,565, filed October 16, 1934. Folding members are indicated at 15 and 16 respectively and a flap inserting member is indicated generally at 17. It is by the conjoint action of these three members that the preliminary folding operation is performed. The first member to act is the flap inserting finger 17. This member comprises a horizontally extending flap bending and guiding portion 18 rigidly affixed to the upper end of an operating arm 19 the lower end of which arm is rotatably supported for movement about a fixed axis. By mechanism hereinafter to be described the arm may be given a swinging or rocking movement about stud 20. Its initial rocking movement, after a container is positioned as shown in Figure 6, is in an anti-clockwise direction and the leading edge of its portion 18 immediately strikes the outer surface of flap 11, deflecting this flap into the position shown in Figure 6, the flap bending readily about the score line intermediate its base and the upper edge of the foldable side wall of the end extension. The movement of the flap inserting finger is continued and, when it reaches the position in which it is shown in Figure 7, the flap 11 is moved into substantially horizontal position. In the meanwhile and by means of other mechanism to be later described movements of the two bending members 15 and 16 have been simultaneously initiated, these bending fingers contacting with the upper edges of the side walls of the foldable extension and the extreme upper end 16' of the bending member 16 having contacted and partially deflected the outer foldable flap 10. The simultaneous movement of folding members 15 and 16 is continued and the for-

ward movement of flap inserting finger 19 halted so that the flat under surface of the portion 18 of this finger comprises a guide for flap 11. This continued motion of the folding members 15 and 16 causes downward deflection of the 5 foldable side walls of the foldable container extension and introduction of the flap 11 into the rapidly closing mouth of the container, as shown in Figure 8, the edge of flap 11 being guided downwardly by the inclined inner surface of the 10 side wall opposite to that to which it is attached, as shown in Figure 8. In Figure 8 it will be observed that the flap inserting finger 19 has been retracted as it is no longer necessary for this member to function as a guide for the flap 11 15 and inasmuch as it is also desirable to remove the flap engaging portion 18 of this member to avoid interference with the upper end 16' of the folding member 16. Simultaneous downward movement of the folding members 15 and 16 is 20 further continued until the upper edges of the sides of the foldable extension meet as shown in Figure 9, the container top being thus closed, the flap 11 being entirely enclosed within the same while the flap 10 still rests against the extension 25 16' of folding member 16. In order to fold flap 10 downwardly, a flap folding and pressure applying member or grooved roller 20 is caused to descend vertically from its retracted or full line position (Figure 9), to its operative or dotted line 30 position. The roller 20 functions while folding members 15 and 16 are still in their operative positions, as shown in Figure 9 and the flap 10 is deflected downwardly thereby to its dotted line position, at least the end positions of the flap 10 35 are so positioned, one edge of one end portion being indicated in dotted lines in Figure 9, the central portion of this flap being pressed tightly against the inclined upper surface of the container. Naturally clearance must be provided to 40 permit the downward movement of roller 20 to contact with the container while the members 15 and 16 are still in contact therewith and the exact shapes of the several members, whereby this clearance is obtained, will be hereinafter 45 more fully described. After the flap folding and pressure applying member 20 is positioned as shown in dotted lines in Figure 9, the folding members 15 and 16 are rocked simultaneously 50 upwardly and outwardly, the container top then being held entirely by the roller 20 at its top and the holding and supporting means at its bottom. It will be observed from an inspection of Figure 9 that portions of the folding member 15 underlie 55 portions of the container flap 10. This member however is formed in two parts, a lower part 15' and an upper part 15², these parts being hingedly connected together in such manner that the part 15² may rotate in a counter-clockwise direction 60 relatively to the part 15' about pivot 21, but may not rotate in the opposite direction. When member 15 therefore begins its clockwise rotation or retracting movement, part 15² will be caused to rotate because of the opposition to its movement by the flap 10, relatively to the part 15' but will eventually be withdrawn from under the flap whereupon part 15² will spring back into alignment with part 15' under the influence of spring 65 22. The functions of the several folding members 15, 16 and 19 have then been fully performed and it is necessary to advance the container to a further station to be acted upon by collapsing and rib forming members. When the conveyor is actuated to bring about this transfer the container moves out from under the roller 20, 70 75

which is still in its lowermost or container holding position, and under stationary guide and holding members 23 rigidly supported upon the frame. The lower rounded edges of these guiding members 23 press tightly against the sides of the container top to hold it in its collapsed condition, as shown in Figure 10. While still held by guiding members 23 the flat inclined side walls of the container top are acted upon by collapsing members 24 which swing downwardly simultaneously from opposite sides of the container, about the axes of shafts 25 upon which they are clamped or otherwise fixed, it being the function of these members to further break down the entire foldable end closure about its several score lines and more particularly to form a central transverse rib by flexing the inclined side walls of the end extension about the score lines 26C, one of which is indicated in Figure 13 and where, up until this time, little if any flexure has occurred. This further breaking down of the foldable end extension of the container is quickly effected and simultaneously a pressure applying and rib holding member 26 is caused to descend, this member having a plurality of rollers 27 mounted in a longitudinally extending recess formed in its lower edge, which rollers bear upon the top of the rib 28 which has just been formed upon the container. Member 26 also includes inner turned edges 26' which bear against the sides of the rib and prevent spreading of the several plies of paper of which the rib is composed, particularly preventing the outer flap 10 from springing upwardly. Once member 26 has been positioned the collapsing members 24 may be retracted, and are retracted, and the container may then be given a further forward movement, as to a machine by means of which a staple or other mechanical fastening device is passed through the several plies of the rib 28 to secure these plies together and effect the permanent closure of the container.

The mechanism for operating the several folding instrumentalities which have just been referred to will now be described. All parts are mounted upon a suitable frame which may have various forms but which, for instance, may include a side frame member 30 and a bridging member 31. Rotatably supported in suitable bearings upon frame 30 is a main drive shaft 32 and fixed upon this shaft are four cam members indicated at 33, 34, 35 and 36. The cam member 33 forms a part of the means for oscillating the flap inserting finger 19, being operatively connected to this finger by means of the lever 37 fixed on shaft 38, lever 39 secured upon the opposite end of this shaft and carrying a segment 40 and the rack 41 one set of teeth of which mesh with segment 40 and a second set of teeth, disposed at right angles thereto, meshing with a segment 42 carried by the hub 43 upon which hub the lower end of the flap inserting finger is also mounted. Obviously, therefore, rotation of cam 33 causes swinging motion of lever 37, lever 37 carrying a roller 44 which extends into the cam-way formed in cam 33, oscillation of shaft 38, rocking of lever 39, reciprocation of rack 41 and oscillation of hub 43 and hence of the folding finger. As will be observed from an inspection of Figure 3, the flap inserting finger is an L-shaped member, the anvil portion 18 of this finger being horizontally disposed and overlying the upper end of folding member 15 so that there are no interferences between members 15 and 19 at any time.

Both folding members 15 and 16 are operated from cam 34 the roller 45 lying within the cam-way of this cam being carried upon the lower end of an arm 46 the upper end of which is fixed upon a shaft 47 so that rotation of cam 34 results in oscillation of shaft 47. Shaft 47 in turn carries two toothed segments 48 and 49 the teeth of these segments meshing with mating teeth formed upon vertically reciprocable racks 50 and 51. Rack 50 is provided with a second set of teeth disposed at right angles to those which mesh with segment 48 the teeth of this second set, or second rack meshing with teeth of segment 52 integral with hub 53, which is the hub upon which the folding member 15 is mounted, member 15 and hub 53 being preferably integral and hub 53 being fixed upon shaft 25. Folding member 16 is integral with a hub 54 rigidly mounted upon the second shaft 25 and which hub also carries a segment 56 the teeth of which mesh with teeth of rack 51, there being a second set of teeth also formed on this rack and facing at an angle of 90° from the teeth which mesh with segment 49. By means of the mechanism just described it will be perceived that both folding members 15 and 16 operate simultaneously at all times and move in opposite directions so as to apply equal pressures to the foldable container end extension in performing their functions.

The flap folding and pressure roller 20 takes its motion from cam 36, this cam effecting rocking movement of bell crank lever 60 one end of which carries the cam roller 61. The opposite end of bell crank 60 is connected by a pin and slot connection to the lower end of a vertically reciprocable rod 62 suitably mounted in a bearing 63 attached to the supporting frame. To the upper end of this rod is connected, also by a pin and slot connection, the end of a lever 64, pivotally mounted upon the frame at 65, a segment 66 being mounted upon the opposite end of the lever the teeth of which mesh with the teeth of a vertically slideable rack 67. The flap folding and pressure applying roller 20 is rotatably carried in a bifurcated supporting member 68 attached to the lower end of rack 67.

The pressure applying and rib holding member 26 takes its motion from the face cam 35. Thus a vertically reciprocable rod 70, slidably mounted in the frame 31, carries at its lower end a cam roller 71 which rests upon cam 35. Rotation of the cam therefore brings about vertical reciprocation of rod 70 and the movements of this rod are communicated to member 26 by means of the lever 72, pivotally supported at 73 and having one end connected to rod 70 by a pin and slot connection and the other end connected, also by a pin and slot connection, to the upper end of a rod 75 mounted for vertical sliding movement in a suitable bearing rigid with the frame, member 26 being suitably secured to the lower end of this rod. A collar shaft upon rod 75 is indicated at 77 and a spring 78 encircling rod 75 has its upper end bearing against the stationary frame. The spring 78 therefore functions to normally maintain rod 75 in elevated position and to therefore maintain cam roller 71 in tight engagement with cam 35. Naturally the several cams and the connecting linkages, racks, segments and levers are so designed and constructed as to produce the desired coordinated movements of the various folding and holding members in the normal operation of the device. From an inspection of Figure 4 it will be readily perceived that the folding members 15 and 16 are so designed as to provide the

necessary clearance for the descent of roller 20 into contact with the container top, the rockable portion 15² of member 15 and the upper end of member 16 being, in effect, bifurcated to provide a central aperture through which roller 20 may descend to contact with the container.

Inasmuch as both collapsing members 24 and also folding members 15 and 16 are fixedly supported upon shafts 25 the collapsing and folding members will be simultaneously operated when shafts 25 are rocked. While folding members 15 and 16 are acting upon the top of one container therefore, to close the same, the collapsing members 24 are simultaneously acting upon the previously closed top of the adjacent container. The collapsing members are so designed and constructed that the ends thereof cooperate in effecting a substantial compression of the base of the rib lying between their adjacent ends, as these members reach the limits of their downward rocking movements. The angles between the base of the rib and the inclined sides of the bottle top are therefore clearly defined and sharpened, compression of the rib base in this manner also compacting the same by pressing the several plies thereof into intimate contact, thus stiffening the rib.

As shown in the drawings, particularly in Figures 6 to 10 inclusive there is mounted on folding member 16 a stop 90 which lies in front of a container which has been moved into position to be acted upon by the folding elements, that is, the corner of the container comes to rest against the stop 90 when the container is properly positioned for folding. Cooperating with this stop is a bracket member 91 mounted on a chain, one link of which is indicated at 92, this bracket having constant contact with the rear wall of the container adjacent the diametrically opposite corner, as it moves along the machine toward the closing means. Chain 92 is fully disclosed in my copending application, Serial No. 748,565, filed October 16, 1934. As the container moves into final position just below the closing elements it strikes stop 90 as aforesaid and by the joint action of stop 90 and bracket 91 it is squared and erected if, by any chance, it has twisted slightly about its vertical axis within the gripping members engaging the same near its bottom, or if it has accidentally been tilted forwardly from the vertical.

While stop 90 will intercept an unclosed container, as shown in Figure 6, when folding member 16 is in inoperative position, it will not intercept a closed container when in this position and hence will not interfere with the movement of a closed container toward the collapsing arms 24.

Having thus described the invention, what is claimed as new and desired to be secured by Letters Patent is:

1. Container end closing mechanism comprising opposed movably mounted container panel engaging and folding members, a container end flap engaging and deflecting member, and means for actuating said members in timed relationship whereby the end flap deflecting member is actuated prior to the panel folding members.

2. Container end closing mechanism comprising means for engaging the projecting end flap of a tubular container and downwardly deflecting the same toward the interior of the container, and means for folding inwardly opposing side walls of the container to enclose said end flap.

3. Container end closing mechanism comprising a flap engaging and inserting finger, means

for actuating the same, opposed container wall folding and deflecting members, and means for simultaneously actuating said members in timed relation to the movements of said finger to effect the insertion and enclosure of said end flap. 5

4. Mechanism for closing the ends of tubular containers having foldable end portions and spaced projecting flaps, including means for initially engaging and inwardly deflecting one of said flaps, and means for thereafter downwardly and inwardly folding those side walls of the foldable end to which the end flaps are secured, said means also folding over the remaining end flap. 10

5. The method of folding the foldable end closure of a tubular container of square cross section, said container being fabricated of relatively stiff paper and the foldable end having four sides each of which is divided by score lines into panels, two opposed sides thereof having longitudinal score lines and being collapsible and the other two having lateral score lines only and being foldable, which comprises acting upon the foldable sides to flex the same bodily inwardly, the collapsible sides being simultaneously collapsed 20 and, after the foldable sides are caused to meet centrally of the container, again acting upon the foldable sides to fold them upon laterally extending score lines, the adjacent panels of the sides being brought into parallelism to comprise 25 members of a central transverse rib. 30

6. The method of closing a stiff paper container which comprises folding opposite side walls bodily toward each other until their upper edges meet, thus forming a peak, and thereafter bringing similar sections of said side walls adjacent the peak line into parallelism to form a central transverse rib. 35

7. In mechanism of the class described, container moving and supporting means, container 40 end folding members positioned to act upon containers carried by said supporting means, and means for correcting the alignment of a container mounted on said supporting means as the container reaches a position to be acted upon by 45 said folding members.

8. Mechanism for relatively folding about scored hinge lines the relatively foldable panels of the collapsible end closure portion of a self-supporting container formed of relatively stiff 50 paper, comprising, means for acting upon and deflecting toward the interior of the container an end flap projecting from the edge of one of said panels, means for acting upon the panel to which the end flap is hingedly connected, and the opposing panel, while said first mentioned means is acting to hold said end flap in deflected position, to swing said panels toward each other to enclose and retain therebetween the said end flap, and means for further acting upon said panels to 55 bring their inner faces into contact with the end flap to thereby form a rib. 60

9. In mechanism of the class described, in combination, means for gripping the base of a stiff paper container and advancing the same with 65 a step by step motion, means for acting upon the top of a container to close the same, said means being positioned adjacent the path of travel of the container and adapted to act when the container is stationary, and means for correcting the 70 position of the container by moving the same within the container gripping means when the container reaches the container closing means. 75

10. The combination set forth in claim 9 in which the last mentioned means includes a par

mounted on the container closing means and movable thereby into and out of the path of travel of the container.

11. The combination set forth in claim 9 in which the last mentioned means includes two co-operating parts one mounted for movement into the path of movement of the upper portion of the container so as to be contacted by the advancing face thereof and the other being adapted to contact with the following face of the container.

12. Mechanism for closing the end of a tubular container having a foldable end portion, including opposed folding members for acting upon opposite sides of said end portion and bodily folding said sides until their upper edges come into contact midway of the container, and second means for engaging said sides respectively, between the contacting edges thereof and the tubular container to further fold said sides and form a central rib.

13. Mechanism for folding the scored end extension of a tubular container comprising means for inwardly folding two opposed sides of said extension until the upper edges of said sides contact centrally of the container, and second means for further acting upon portions only of said folded sides to bend said sides about score lines intermediate the container and the line of contact between said sides and parallel to the central line of contact of said sides, thus forming a central rib.

14. The method of folding the scored foldable end closure portion of a tubular container which comprises folding simultaneously toward each other two opposing scored side walls until they are brought into line contact centrally of the

container to form a peaked structure, and thereafter breaking down or further folding each of the folded sides by the application of opposed forces thereto to form a central rib.

15. The method of folding the foldable end closure of a tubular container fabricated of relatively stiff paper and which end closure is divided into four sides, two opposing sides being foldable and the other two being collapsible, by score lines, which comprises collapsing the opposing collapsible sides of the end closure by folding the panels thereof relatively to each other, folding the other two opposing sides bodily and without breaking them along the score lines, and thereafter further breaking down the foldable sides along score lines by the application of opposed forces to form a central transverse rib.

16. In a mechanism of the class described, the combination with a conveyor of container end folding means, rib forming means, of means for applying axial pressure upon a container rib subsequent to its formation, which means positively supports the rib against lateral distortion.

17. In mechanism of the class described, container end folding means for forming a peaked end structure, means for acting upon said peaked structure to form a centrally ribbed structure, a conveyor for supporting the bottom of a container and moving the same from one such means to the other, and means for supporting and maintaining the peaked structure as it is moved into position to be acted upon by said rib forming structure, said last mentioned means including a grooved roller.

HENRY T. SCOTT. 35
